UNITED STATES PATENT OFFICE

JOHN L. GARRETSON, OF BUFFALO, NEW YORK

DEVELOPING APPARATUS

Application filed March 23, 1929. Serial No. 349,364.

This invention relates to improvements in developing apparatus which is adapted for daylight use particularly in connection with X-ray films. These films, as now manufactured, are individually packed in separate containers or envelopes by which they are protected against exposure to light. In making X-ray photographs, the films are left in their containers while the photographs are being taken and removed therefrom only when they are to be developed. During their removal and the subsequent developing process the films must be protected against exposure to light which is ordinarily accomplished by conducting such operations in a dark room.

The principal object of the invention is to eliminate the necessity of the dark room and to enable daylight work by the use of apparatus for thoroughly protecting the films against exposure to light during their removal from their containers and during the subsequent developing, washing and fixing operations.

Another object is to provide means for mechanically withdrawing the films from their containers.

A further object is to provide a casing into which the films drop when they are withdrawn from their containers and by which they may be freely and safely carried in daylight and subjected to the various operations of the developing process.

An embodiment of the invention is illustrated in the accompanying drawings, wherein:

Figure 1 is a perspective of the tank with its cover fitted.

Figure 2 is a perspective of the casing with its hinged door swung open.

Figure 3 is a perspective of the carriage frame.

Figure 4 is a longitudinal section of a suitable film pack.

Figure 5 is a perspective of the same.

Figure 6 is a perspective showing the element partly withdrawn.

Figures 7 and 8 are sectional views respectively showing the apparatus as it appears

immediately before and after the mechanical withdrawal of the element.

The developing apparatus essentially includes an outer casing or tank 1, an inner casing 2 and a carriage frame 3 which is composed of a plurality of plates symmetrically arranged and secured in spaced parallel relation to delimit a series of separate chambers. These parts may be composed of any suitable material and fashioned in any suitable shape.

The tank 1 is provided with a closed end or bottom 4 and with a removable cover 5, the latter carrying a plunger 6 which normally is urged outwardly by a spring 7. The casing 2 is freely insertable or removable from the tank 1.

The inner casing 2 preferably conforms in shape to the tank 1 and is provided with a closed end or bottom 9 and a hinged cover 10, the latter being weighted to close automatically unless otherwise held open. One side of the inner casing is provided with a vertical extension 11 which is formed to provide a vertical guideway leading into the casing 2. The upper end of the vertical extension 11 carries a pin 13 which may be utilized as a bail for carrying the inner casing from one point to another and for inserting or removing it from the tank. The bail 13 also cooperates with the carriage frame 3 as described herein-after.

Each open chamber of the carriage frame 3 is adapted to receive a film pack containing the photographic element that is to be developed. The ordinary film pack indicated at P consists of a photographic element or film 14 which is contained within an envelope 15. The element 14 in dark room work is ordinarily removed by tearing away the envelope. For use with the present apparatus, however, one end of the envelope 15 is provided with a perforated tab 15a while the other end of the envelope is arranged to permit endwise withdrawal of the element 14, the latter being provided with a perforated tab 14a to facilitate such withdrawal. With this arrangement the element 14 may be withdrawn from the envelope 15 by pulling the tabs 14a and 15a in opposite directions.

The element tab 14a of each pack is secured

to the carriage frame by passing a pin 16 transversely through suitable apertures in the carriage frame at one end thereof, the pin 16 being at the same time passed through 5 the apertures of the photographic element tabs 14a. With the packs thus secured, the carriage frame may be supported from the bail 13 by threading the apertures of the envelope tabs 15a over the bail. By proceeding 10 in this manner, it is evident that the carriage frame is supported from the bail 13 by virtue of the binding action between the photographic elements 14 and their respective envelopes 15. This operation may be conducted 15 when the casing 2 is placed within or without the tank 1. At any rate, the casing 2 is arranged within the tank 1 with its hinged door 10 open, the door being held in this position by the carriage frame 3. The cover 5 is now 20 properly fitted and the plunger 6 pressed inward. As the plunger 6 moves inward, it is brought into engagement with the plates of the carriage member 3 forcing the latter downward. The photographic elements 14 25 being secured to the carriage frame move with it and are thus withdrawn from their respective envelopes, the envelopes being held in place through their engagement with the bail 13. When the carriage frame has been pushed 30 downward to a point where there is little or no binding force between the photographic elements 14 and their envelopes 15, the carriage frame drops by gravity and, in dropping is guided into the inner casing 2 by the 35 guideway of the vertical extension 11. The hinged door 10 of the inner casing 2 now closes automatically thereby completely enclosing the carriage frame and photographic elements 14. The casing 2 thus affords full 40 protection to the photographic elements 14 and it may, therefore, be withdrawn from the tank 1 and exposed to light without exposing the photographic elements. The envelopes 15 may be removed at any time simply by slipping them from the bail 13.

If desired, the photographic elements may 45 be subjected to the developing bath while they remain within the tank 1. Obviously the developer may be placed within the tank before or after the photographic elements are separated from their envelopes. In any case, the 50 elements are subjected to the developer for the desired length of time and then removed by removing the casing 2. To facilitate the flow of the developer and other baths into 55 and out of the casing 2, the latter is provided with apertures 17 which are formed in such of its sides as extend parallel to the plates of the carriage frame 3. By so doing, the plates 60 of the frame 3 prevent any light which may pass through the casing apertures 17—when the casing 2 is removed from the tank 1—from striking the photographic elements 14.

When the casing 2 has been withdrawn 65 from the tank 1, the photographic elements

14 may be subjected to the washing and fixing baths simply by placing the casing 2 into the same. After the developing process has been completed, the elements 14 may be removed from the casing 2 by withdrawing the carriage frame 3 therefrom and then removing the pin 16 which secures the elements to the frame.

Having described my invention, I claim:

1. In a photographic developing apparatus including a casing, a carriage member of the class described comprising a body arranged to provide a chamber which is adapted to receive a film pack composed of a photographic film contained within an envelope and slidably removable from one end thereof, and means for securing said body to one element of said pack.

2. In a photographic developing apparatus including a casing, a carriage member of the class described comprising a body arranged to provide a chamber which is adapted to receive a film pack composed of a photographic element contained within an envelope and arranged for endwise withdrawal from one end thereof, and means for securing said body to said element at the withdrawal end of the envelope.

3. In a photographic developing apparatus, a carriage member of the class described comprising a series of plates secured in spaced parallel arrangement to provide a series of open ended chambers, each chamber being adapted to receive a film pack composed of a photographic element contained within an envelope and arranged for endwise withdrawal from one end thereof, and means extending transversely through each chamber and adapted for engagement with the withdrawal end of a photographic element to secure the same to said member.

4. In a photographic developing apparatus including a casing, the combination of a carriage arranged to provide a chamber which is adapted to receive a film pack composed of a photographic film contained within an envelope and slidably removable from one end thereof, means adapted for engagement with one element of said pack at one end thereof to secure the same to said carriage, means adapted for securing to the other element of said pack at the opposite end thereof and means for relatively separating the securing means first and last mentioned.

5. In a photographic developing apparatus including a casing, the combination of a carriage arranged to provide an open ended chamber which is adapted to receive a film pack composed of a photographic element contained within an envelope and arranged for endwise withdrawal from one end thereof, means carried by said carriage and adapted for engagement with the photographic element of said pack at the withdrawal end

- thereof, means adapted for securement to the envelope of said pack at the opposite end thereof and means for relatively separating the element and envelope securing means.
6. In a photographic developing apparatus, the combination of tank, means adapted for engagement with one end of the envelope of a film pack, the opposite end of which is arranged to permit the withdrawal of the photographic element contained therein, to support the pack within said tank, means adapted for securement to the withdrawal end of said photographic element and means for moving said means last mentioned away from said means first mentioned whereby to effect the withdrawal of a photographic element from the envelope of a film pack secured between said first and last mentioned means while moving said element toward the bottom of said tank.
7. In a photographic developing apparatus, the combination of a tank arranged to provide a dark chamber, means adapted for engagement with one end of the envelope of a film pack, the opposite end of which is arranged to permit the withdrawal of the photographic element contained therein, to support the pack within said tank, means adapted for securement to the withdrawal end of said photographic element and means manually controlled from the exterior of said tank for moving said means last mentioned away from said means first mentioned whereby to effect the withdrawal of a photographic element from the envelope of a film pack secured between said first and last mentioned means while moving said element toward the bottom of said tank.
8. In a photographic developing apparatus, the combination of a tank arranged to provide a dark chamber, a body arranged to provide a chamber which is adapted to receive a film pack composed of a photographic element contained within an envelope and arranged for endwise withdrawal from one end thereof, means adapted for securing the withdrawal end of said element to said body, means adapted for engagement with the envelope at the opposite end thereof to support said body within said tank and a plunger extending through and carried by said tank and adapted for movement into said tank to engage and move said body away from the envelope engaging means thereby to effect the withdrawal of the photographic element from the engaged envelope.
9. In a photographic developing apparatus including a casing, the combination of means adapted to support over said casing a film pack composed of a photographic element contained within an envelope and arranged for endwise withdrawal from one end thereof, said means being arranged for supporting engagement with the envelope of said pack, means adapted for securement to the withdrawal end of said element and for movement into said casing and away from said envelope engaging means and means for so moving said element engaging means.
10. In a photographic developing apparatus, the combination of a casing having an opening which is adapted to be closed by a hinged cover, a member secured to said casing and providing a vertical guideway leading into said casing through said opening, a body arranged to provide an open ended chamber which is adapted to receive a film pack composed of a photographic element contained within an envelope and arranged for endwise withdrawal from one end thereof, means carried by said body and adapted for engagement with the photographic element of said pack at the withdrawal end thereof, means carried by the upper end of said member and adapted for engagement with the envelope of said pack at the end opposite from the element withdrawal end to support said body along said guideway and over said casing, said body depending thereunder to an extent sufficient to hold said cover in its open position after it has been moved thereto, and means for effecting a relative separating movement between said body and said envelope engaging means so as to withdraw said element from said envelope whereby said body together with said element is free to fall along said guideway and into said casing, the movement of said body rendering said cover free to move to its closed position.
11. In a photographic developing apparatus, the combination of a tank having a removable cover, said tank being arranged to provide a dark chamber, a casing having an opening which is adapted to be closed by a hinged cover, said casing being insertable into said tank, a member secured to said casing and providing a vertical guideway leading into said casing through said opening, a body arranged to provide an open ended chamber which is adapted to receive a film pack composed of a photographic element contained within an envelope and arranged for endwise withdrawal from one end thereof, means carried by said body and adapted for engagement with the photographic element of said pack at the withdrawal end thereof, means carried by the upper end of said member and adapted for engagement with the envelope of said pack at the end opposite from the element withdrawal end to support said body along said guideway and over said casing, said body depending thereunder to an extent sufficient to hold said cover in its open position after it has been moved thereto, and means controlled from the exterior of said tank for effecting a relative separating movement between said body and said envelope engaging means so as to withdraw said element from said envelope.

whereby said body together with said element is free to fall along said guideway and into said casing, the movement of said body rendering said cover free to move to its closed position.

- 5 12. In a photographic developing apparatus, the combination of a tank arranged to provide a dark chamber, a casing insertable into said tank, said casing having a hinged cover and arranged to provide a dark chamber, means for supporting within said tank and over said casing a film pack having a photographic element contained within an envelope, and means controlled from the exterior of said tank for withdrawing the photographic element from said envelope and transferring it to the chamber provided by said casing, said hinged cover being arranged in its open position prior to the transfer of said element and adapted for movement to its closed position after the transfer of said elements.

- 10 13. In a photographic developing apparatus, the combination of a tank arranged to provide a dark chamber and adapted to contain a photographic element developing bath, a casing insertable into said tank and provided with apertures for the flow of the developer between said tank and casing, said casing having a hinged cover, means for supporting within said tank and over said casing a film pack having a photographic element contained within an envelope, and means controlled from the exterior of said tank for withdrawing the photographic element from said envelope and transferring it to the chamber provided by said casing whereby it is subject to the developer contained in said casing, said hinged cover being arranged in its open position prior to the transfer of said element and adapted for movement to its closed position after the transfer of said element and means for preventing light from passing through the apertures in said casing and striking the photographic elements whereby the casing may be removed from said tank and exposed to light without exposing said elements.

15 In testimony whereof I hereby affix my signature.

JOHN L. GARRETSON.
